(57) **CLAIM**

The ornamental design for a mounting stand for image capture using a mobile device, as shown and described.

DESCRIPTION

FIG. 1 is a front perspective view of a mounting stand for image capture using a mobile device showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another front perspective view thereof.

The broken lines in the figures show portions of the mounting stand for image capture using a mobile device that form no part of the claimed design. Additionally, the broken lines in FIG. 8 showing an exemplary mobile device form no part of the claimed design.

1 Claim, 8 Drawing Sheets
